Panther Valley, Hackettstown, N.J. 07840

Filed Sept. 28, 1973, Ser. No. 401,754

Term of patent 14 years

Int. Cl. D9—05

U.S. Cl. D9—192

FIG. 1 is a perspective view of a tearable blister package showing my new design;

FIG. 2 is a top plan view thereof;

FIG. 3 is a side elevational view;

FIG. 4 is a front end elevational view;

FIG. 5 is a rear end elevational view.

The bottom is plain and unornamented save for the two slits extending inwardly from the outer perimeter as seen in FIG. 2.

I claim:

The ornamental design for a tearable blister package, substantially as shown and described.
